UNITED STATES PATENT OFFICE.

FRANK A. WHITTEN, OF DETROIT, MICHIGAN, ASSIGNOR TO GENERAL MOTORS CORPORATION, OF DETROIT, MICHIGAN, A CORPORATION OF DELAWARE.

MOTOR VEHICLE.

Application filed January 16, 1919. Serial No. 271,504.

To all whom it may concern:

Be it known that I, FRANK A. WHITTEN, a citizen of the United States, and resident of Detroit, Wayne County, State of Michigan, have invented certain new and useful Improvements in Motor Vehicles, of which the following is a specification.

The present invention has reference to engine supporting means for motor vehicles, its object being to provide a support wherein the secondary twisting stresses in the engine casing, due to racking and twisting of the vehicle frame, are substantially eliminated.

One important feature of the invention consists in a front support for the engine having a narrow flange-like bearing element on the engine arranged to be received in a bearing on the frame, the parts being so constructed and arranged that the bearing element may tilt both longitudinally and transversely in the bearing and may slide slightly bodily in the bearing. The various twisting stresses and other stresses are thus eliminated in the frame, the engine supports and the engine unit and accessory parts, and provision is also made for expansion or contraction or for slight variations in construction.

The invention also consists in an engine support of the nature stated wherein the bearing includes a resiliently held cap, whereby pounding of the engine and the consequent wear and noise, incident to ordinary constructions is avoided.

The invention further consists in rear supports for the engine so constructed that the latter is resiliently held down on either side and is free to tilt slightly without inducing objectionable twisting stresses in its arms. The invention further consists in means whereby the engine is carried directly on the vehicle frame in such manner that the proper alignment of the engine shaft is more readily permitted than heretofore.

The invention also consists in the details of construction shown, described and claimed. Among other things, these details permit a ready interchange of motors, avoid the danger of stripping the threads of the engine retaining bolts and insure a proper lubrication of the front bearing.

In the drawings, Fig. 1 is a part side elevation, part section showing a preferred embodiment of the invention. Fig. 2 is a frag-

mentary view looking from the left in Fig. 55 1, portions of the rear supports being broken away. Fig. 3 is an enlarged front view showing the front support, Fig. 4 is a section on the line IV—IV of Fig. 3. Fig. 5 is a fragmentary front elevation showing 60 a modification in the trunnion bearing, and Fig. 6 is a section on the line VI—VI of Fig. 5. Figs. 7 and 8 are fragmentary views of alternative constructions of the rear and front supports respectively. 65

The side bars 1 and front cross bar 2 of the vehicle frame are of ordinary construction, and the engine 3, as usual, includes a rigid upper crank case section 4 comprising a flywheel housing 5 and a removable lower 70 crank case section 6.

The section 4 includes a forward extension 7 which, in the embodiment of the invention that appears in the drawings, forms a chamber for timing gears (not shown). 75 This extension is continued as a cover plate 8 and beyond the latter, as a tubular bearing or enclosure 9 for the usual cranking shaft 10. Evidently the whole extension might be made in a single piece, but it is preferred 80 to make the cover plate separate from the engine casing, and to also make the bearing 9 separate from the cover. As shown, the cover plate is connected to the casing by cap screws 12, and includes at its front end (Fig. 85 4) an annular flange 13 to which the bearing 9 is secured in like manner by cap screws 14. Formed either on the cover plate 8 or the bearing 9—preferably on the latter, as it may then be more readily machined—90 is a narrow flange 15 which rests in a trunnion bearing 16 secured to the cross bar 2 by bolts 17. The bearing 16, in the embodiment shown, is hollowed out at 18 to receive the heads of the lower cap screws 14, 95 and includes the loose cap 19 that conforms to the upper half of the flange 15 and is connected to the rest of the bearing by bolts 20. Springs 21, interposed between the nuts 22 of the bolts and the cap, hold the latter 100 firmly and yet resiliently, in engagement with the flange.

The rear end portion of the casing section 4 (as shown, the fly wheel housing 5) is provided with oppositely disposed outwardly 105 extending arms or feet 25, that rest on brackets 26 riveted or otherwise secured to the side bars, the arms being continued

down along the inner faces of the brackets at 27 to transmit side thrusts from the engine to the frame and vice versa. For the purpose of preventing the elements 5 25 from rising from the brackets, the bolts 28 are provided, the holes in the brackets being of appreciably greater diameter than that of the bolts, whereby sufficient lateral shifting is allowed to bring the corresponding 10 surface 27 into engagement with the bracket, without tending to shear the bolts. Springs 29, interposed between the nuts of the bolts and the brackets, resiliently hold the feet down to the supports. These springs 15 are of importance in that the racking and twisting of the frame (which tends to raise either the rear or the front edge of the arm from the bracket) may freely take place without inducing the heavy twisting stresses 20 in the arms which would otherwise result, and which are a constant source of breakage.

It is evident that the flange 15 and bearing 16-19 permit slight relative longitudinal movement between the engine casing and the frame, and that the flange 15, being narrow, also permits relative tilting between the engine and the front cross bar. Were the flanges of considerable length, local bending stresses, which would tend to cause 30 breakage, would be set up; and were the cap fixed to the rest of the bearing by a non-resilient connection, the ordinary variations of manufacture or a slight wear would permit the engine to pound up and down, thus 35 causing aggravated wear and increased looseness. There being no lost motion in the connection at any time, wear is substantially eliminated.

It is evident that various changes may be 40 made in the details of construction without departing from the spirit of the invention. For example, Figs. 5 and 6, the overhanging bracket or bearing 16 may be superseded by the pillow block 30 that rests directly 45 on the upper surface of the front cross bar 31 and is held in place thereon by cap screws or bolts 32 which pass up through the cross bar and through a spacer or filler 33. The cap screws 34, whereby the cap 50 19 and springs 21 are in this instance held in place are aligned with the screws 32, so that the tapping of the threads in the pillow block or trunnion bearing is simplified.

In either case, the cap 19 may be provided 55 with a grease cup 35 whereby the corresponding bearing is kept lubricated.

The construction is very much less expensive, more compact, and generally more efficient than the resilient engine supports, including 60 a sub-frame, which have heretofore been used to some extent; it also required no careful machining operations and is, in that particular less expensive than ordinary supports in which the engine rests directly 65 on the frame or on brackets carried by the

frame. While it is primarily intended for use on trucks and other heavy duty vehicles, it may, of course be applied to ordinary pleasure vehicles.

In Figs. 7 and 8 the supporting members 70 are shown integral with the crank case base or oil pan, which construction allows of quick and economical replacement or repair of damaged parts.

To repeat:—the engine is resiliently held 75 down and is free for slight universal tilting movement at all three points of support, at its rear end it may shift slightly laterally in either direction to transmit the stresses directly from and to the frame and 80 to relieve the bolts from shear; the front and rear edges of the rear supporting arms may also rise slightly from the corresponding edges of the brackets, which does away with the tendency to strip the threads of 85 the bolts or to break the arms; and the front portion or even the whole of the engine may shift slightly bodily longitudinally of the frame to compensate for thermal changes or to afford slight initial adjustment. 90 Withal, the construction is stiff, in so far as the combined engine and trunnion is concerned, there being no relative movement between these parts and therefore no opportunity for wear and looseness.

I am aware that three-point supports have been used for various equipment in connection with motor vehicles, and also that resilient connections have been provided. I do not broadly claim the same as 100 novel, nor do I claim a construction where- 95 in an auxiliary frame is employed to support a power plant, the frame being in turn resiliently supported on the regular vehicle frame, but I do claim as novel the par- 105 ticular arrangement of resilient supports whereby a minimum number of parts is re- 110 quired and the assembly thereof greatly simplified, whereby the many advantages, as set forth in the present specification, are attained.

I claim:—

1. In a motor vehicle, a frame, an engine, means for supporting the engine on the frame, said means comprising a narrow 115 flange-like element fixed to the engine, a bearing in which the element is received and which bearing surrounds said flange- 120 like element, said bearing including a resil- 110 iently held cap, whereby the element is per- mitted to tilt and whereby wear is avoided.

2. In a motor vehicle, a front cross bar, an engine, means for supporting the front portion of the engine on the cross bar, said means including an extension on the engine 125 having a narrow flange-like bearing ele- 130 ment, a bearing for said element carried by the cross bar and which bearing surrounds said flange-like element, said bearing in- 135 cluding a resiliently held cap, whereby the 130

engine may tilt transversely and longitudinally of the vehicle without inducing objectionable stresses in the supporting means.

3. A motor vehicle comprising a frame, 5 an engine, and means for supporting an end portion of the engine on the frame and for permitting universal relative tilting movement between the engine and frame and for also allowing said end portion of the engine 10 to slide longitudinally in respect to the frame, said means including a narrow trunnion bearing surface on the engine and a longer bearing on the frame surrounding said trunnion bearing surface and within which 15 the same is received.
4. In a motor vehicle, a front cross bar, an engine including a hollow forward extension adapted to receive a starter crank shaft, said extension including a flange having a cylindrical outer surface, a bearing 20 carried by the cross bar and having a cylindrical surface on which the first mentioned surface rests and is slidable, said extension being free for universal swinging movement 25 relatively to the bearing.
5. In a motor vehicle, an engine casing including a portion forming a chamber

adapted to receive gearing, a hollow cover for said chamber and extending forwardly therefrom, a tubular member connected to 30 the cover and adapted to enclose a starter crank shaft, and a bearing surrounding the tubular member for supporting the engine for slight universal tilting movement.

6. In a motor vehicle, an engine, including 35 a casing, a tubular member rigid with the casing and adapted to enclose a starter crank shaft, and a bearing engaging the exterior of said tubular member, the parts being so constructed and arranged that the 40 tubular member may slide slightly longitudinally of the engine and may also have limited universal swinging movement relatively to the bearing.

7. In a motor vehicle, a front cross bar, 45 an engine having a forward extension having a narrow ring-like bearing surface, a bearing in which said surface is received, said bearing including a resiliently held cap having thereon a grease cup whereby the 50 ring-like surface is lubricated.

In testimony whereof I affix my signature.

FRANK A. WHITTEN.
